UNITED STATES PATENT OFFICE.

JOHN J. McCOMISH, OF PROVIDENCE, RHODE ISLAND, ASSIGNOR OF ONE-HALF TO JOHN J. SHANAHAN, OF SAME PLACE.

STOP-MOTION FOR LOOMS.

SPECIFICATION forming part of Letters Patent No. 399,917, dated March 19, 1889.

Application filed November 8, 1887. Serial No. 254,618. (No model.)

To all whom it may concern:

Be it known that I, JOHN J. McCOMISH, of Providence, in the county of Providence and State of Rhode Island, have invented certain new and useful Improvements in Stop-Motions for Looms, of which the following is a full, clear, and exact description, reference being had to the accompanying drawings, forming part of this specification.

This invention relates to what is known as a "stop-motion" mechanism, which is a self-acting apparatus for instantly stopping a loom when the loom is not in proper operative condition.

The objects of my invention are to provide a stop-motion which will at once arrest the motion of the loom when either the shuttle pockets or boxes at the respective ends of the race each contains a shuttle, or when neither of such boxes contains a shuttle. Since both of the aforesaid conditions are defective and are productive of smashes and other accidents, it is necessary that the loom be at once stopped under such conditions.

To the aforesaid purposes the gist of my invention consists in providing two independently-acting detector-fingers, one for each of the respective drop-boxes, which may act independently or together upon mechanism connected with the stop-motion rod, which operates the shipper mechanism under either of the aforesaid defective conditions of the loom.

My invention further consists in the certain novel and peculiar construction and arrangement of the several parts of the mechanism, all as hereinafter fully described and claimed.

In order that my invention may be fully understood, I have illustrated in the accompanying drawings, and will proceed to describe, the best form thereof so far devised by me, with the knowledge that such form may be variously modified without, however, making a substantial departure from the spirit of my invention.

In the accompanying drawings, Figure 1 is a top plan view of sufficient parts of an ordinary drop-box loom to illustrate the use of my improvements, which are shown embodied

therein, the loom-arch being in section. Fig. 2 is a detailed view of a part of the loom shown in Fig. 1. Fig. 3 is a diagrammatic plan view showing the positions of the connecting-lever relatively to the lay, which is shown in part. Fig. 4 is a front view, partly in section, of a portion of the loom shown in Fig. 1, and having my improvements attached. Fig. 5 is an end view of a portion of the loom with part of my attached mechanism which actuates the shipper mechanism, and Fig. 6 is a sectional view taken on line X X in Fig. 5. Fig. 7 is an enlarged sectional view taken on line y y in Fig. 1. Fig. 8 is a detailed view of the lay and the rocker pivoted thereto, as shown in Fig. 7.

In the said drawings like letters of reference designate corresponding parts throughout.

Referring to the drawings, the letter A designates the framing of an ordinary drop-box loom, of which B is the warp-beam, C the breast-beam, and D is the lay, which is provided at the respective ends with the vertically-shiftable drop-boxes E for the shuttles F. The drop-boxes E are furnished with the swells or binders G, having each a spring, G', acting thereon. The purpose and operation of these swells G are well known; and my invention essentially consists in utilizing the swells to detect the defect in the position of the shuttles and introducing detector devices or fingers, as H and H', to co-operate one with each of the set of swells of the respective drop-boxes, so that such detector-fingers are independently movable, and may act separately or together upon the stopping mechanism of the loom.

At the ends of the lay, and on the forward face thereof, are mounted in bearings I¹, so as to turn, the detector rock-shafts I' and I², upon the outer ends of which are made fast the detector-fingers H and H', respectively, so that the presence of a shuttle in the box or pocket under the ends of the fingers will cause the same to be thrown outward from the box, while the absence of the shuttles will allow the fingers to incline in toward the boxes. To the inner ends of the detector-shafts are secured the depending fixed arms M' and M²,

respectively, which are alike slotted at M at the lower end, and in these slots M rest the respective cylindrical ends of the connecting-lever N, which is formed with a central eye 5 to receive the journal-stud N', cast on the end of the L-shaped rocker O, which is swiveled at the upper end to the bracket N², fixed upon the lay.

At the angle of the L-shaped rocker O is a 10 perforation, N³, by means of which is hinged thereto the link O², which at its other end is pivoted to the end of the bar P', rigidly attached to the turnable stop-motion rod P, which is mounted to turn in the bearings P², 15 secured to the under side of the lay. The stop-rod P is provided with the stop finger or dagger J, having the retracting-spring L for holding it in high position, and the end of this finger is formed with the lateral hooks J', 20 which are designed to hook and lock with the suitably-forked upper end, Q, of the vibrating arm R, which vibrates on the pin R², and has its inward throw limited by the stop S'. The hooked extension R' of the vibrating 25 arm R is designed to engage with the fixed turn-bar R² on the shipper-shaft L², so as to draw the bar inwardly as the vibrating arm rocks toward the warp-beam. The shipper-shaft L² is mounted to turn in the framing, 30 and at one end is provided with the shipper-lever L³, connected with the belt-shipper rod L⁴ by means of the link L⁵, so that upon the inward movement of the vibrating arm R the belt-shipper rod L⁴ may be operated to ship 35 the driving-belt (shown in Fig. 1) and stop the loom. The shipper-shaft L² is also operated to shift the belt when the stop-finger J is in the high position shown in full lines in Fig. 1 by means of the finger striking against 40 the push-piece K, which is pivoted to the breast-beam and engages with the end of the shipper-arm L', fast upon the shipper-shaft L², so that when the stop-finger pushes upon one end of the push-piece the other end thereof 45 will move inward and force the shipper-arm inward, so as to turn the shipper-shaft L² and stop the motion of the loom. The outward throw of the push-piece K is limited by the stop S. 50 To obviate the wear and tear on the swell-fingers G and the detector-fingers H and H', and to prevent the boxes from sticking, I provide the cam-arms T on each detector-shaft I' and I², and these are arranged to engage 55 cams T', fixed to the breast-beam C, so as to slightly depress the cam-arms at the end of the stroke, and thus throw the detector-fingers off their respective swells, whereby the pressure may be relieved at such time. 60 The operation of my improved stop-motion is as follows: When the loom is running, if the shuttle about to be thrown has an empty pocket to receive it at the end of its flight, the swell adjacent to such shuttle will press 65 the detector-finger engaging the same outward, which will accordingly move the corresponding end of the connecting-lever N in to-

ward the lay, while the empty pocket about to receive such shuttle will obviously cause the co-operating detector-finger to lie in toward the box, and will accordingly throw the corresponding end of the connecting-lever N out from the lay. This is the proper running condition of the loom, and under such condition the connecting-lever N will assume the 70 inclined dotted-line position shown in the diagram in Fig. 3, or in the reverse inclined position, in consequence of which inclined position the stop-finger will be maintained in the dotted-line position shown in Fig. 7, midway between the high and low positions, and will thereby clear both the push-piece K and the head of the vibrating arm R, and of course will not stop the running of the loom. Under the defective condition of two shuttles coming in position to be thrown through the shed, 75 both detector-fingers will be alike deflected from the lay, and accordingly the connecting-lever N will be moved to its inward position parallel with the lay, as shown in dotted lines 80 in Fig. 3, and this will cause the stop-finger to be lowered to the lowest position, (shown in broken lines in Fig. 7,) so as to engage and latch with the vibrating arm R, which will thereupon be moved inward by the lay as it 85 moves away from the breast-beam, thereby turning the shipper-shaft L² and stopping the loom, as hereinbefore described. Under the defective condition of the failure of the throwing of a shuttle completely through the shed 90 and into the opposite box both detector-fingers H and H' will accordingly be inclined in toward the boxes, which, as before explained, will move the connecting-lever N into the full-line position shown in Fig. 3, and accordingly 95 elevate the stop-finger J to the high position shown in Fig. 7, thereby operating the push-piece K to turn the shipper-shaft L² and stop the loom. 100

Having thus described my invention, I claim 110 as new and desire to secure by Letters Patent—

1. The combination, as hereinbefore set forth, with the lay of a loom and the drop-boxes at the respective ends thereof provided with swells, of the independently-movable detector-fingers appropriate to engage the swells thereof and mounted on independent rocking shafts, the inner ends of which rocking shafts are provided with arms, a lever mounted on the rocker and connecting the arms of the two 115 independent rock-shafts, the rocker, the stop-motion rod, and devices connecting said rocker with said rod, whereby the loom may be stopped when the detector-fingers assume certain predetermined positions, substantially as and for 120 the purpose herein described.

2. The combination, with the lay of a loom, the drop-boxes provided with swells, the independently-movable detector-fingers, the detector-shafts for the fingers, the arms attached 125 to the detector-shafts, the rocker, the connecting-lever mounted on said rocker and operated by the said arms, and the stop-motion rod provided with the stop-finger and con-

ected to the said rocker by the link, of the push-piece or vibrating arm constructed to operate a shipping device, substantially as herein described.

5 3. The combination, as hereinbefore set forth, with the lay and the drop-boxes therefor provided with the swell-fingers, of the independently-movable detector-shafts, each provided with a detector-finger for engaging 10 the swells of the respective drop-boxes, a stop-motion rod and the rocker connected therewith and operating the rod, the connecting-lever swiveled to the rocker, and the arm rigidly mounted on each detector-shaft and 15 loosely connected with the respective ends of the connecting-lever, substantially as described.

4. The combination, as hereinbefore set forth, with the lay D, provided with the drop-boxes E, having the swells G, of the independently-movable detector-fingers H and H', the shafts I' and I², the arms M' and M², the connecting-lever N, the rocker O, and the stop-motion rod P, connected therewith and provided with the stop-finger J, the push-piece K, vibrating arm R, and the devices operated thereby, whereby the loom may be stopped when the detector-fingers and stop-finger are similarly deflected, substantially as herein 30 shown and described.

5. The combination, as hereinbefore set forth, with the lay D, having the drop-boxes E, provided with the swells G, of the independently-movable detector-fingers H and H', engaging 35 the sets of swells of the respective drop-boxes, the rocking detector-shafts I' and I², upon which the said respective detector-fingers are mounted, the stop-motion rod P, and the pivoted rocker O, connected therewith and 40 actuating the same, the connecting-lever N, swiveled to the rocker O, and the arms M' and M², intermediate the respective detector-shafts I' and I² and the ends of the connecting-lever N, substantially as and for the purpose herein 45 described.

6. The combination, as hereinbefore set forth, with the lay, the drop-boxes therefor, and the swells, of the independently-operating detector-shafts I' and I², provided with the 50 detector-fingers H and H', respectively, and having the arms M' and M² mounted thereon, respectively, the stop-rod P, the pivoted rocker O, and the link O² and bar P', intermediate the stop-rod and the rocker, and the connect-

ing-lever N, swiveled to the rocker and engaging 55 with its ends the said arms M' and M², respectively, substantially as and for the purpose herein described.

7. The combination, as hereinbefore set forth, with the independently-movable detector-shafts I' and I², provided with the detector-fingers H and H' and the arms M' and M², respectively, of the stop-rod provided with the hooked stop-finger J, the pivoted rocker O, and the link O² and bar P', intermediate the 60 said rocker and stop-rod, the connecting-lever N, swiveled on rocker O and engaging with the ends the said respective arms M' and M², the shipper-shaft L², provided with the turn-bar R² and the shipper-arm L', the pivoted 65 push-piece K, for engaging the said shipper-arm, and the vibrating arm R, provided with the hooked head Q and having the hooked extension R', for engaging the turn-bar R², substantially as and for the purpose herein 70 described.

8. The combination, as hereinbefore set forth, with the independently-movable detector-shafts I' and I², provided with the detector-fingers H and H' and the fixed arms M' and M², 80 respectively, of the stop-rod P, provided with the hooked stop-finger J, the pivoted rocker O, and the link O² and bar P', intermediate the rod P and rocker O, the connecting-lever N, swiveled on the rocker O and engaging the 85 arms M' and M², respectively, the shipper-shaft L², provided with the turn-bar R², and the vibrating arm R, having the hooked head and provided with the hooked extension R', for engaging the bar R², substantially as and for 90 the purpose herein described.

9. The combination, as hereinbefore set forth, with the independently-movable detector-shafts I' and I², provided with the detector-fingers H and H' and the fixed arms M' and M², 95 respectively, of the stop-rod P, provided with the stop-finger J, the pivoted rocker O, and the link O² and bar P', intermediate the rod P and rocker O, the connecting-lever N, swiveled to the rocker O, the shipper-shaft L², provided with the shipper-arm L', and the pivoted 100 push-piece K, engaged by the finger J, substantially as and for the purpose herein described.

JNO. J. McCOMISH.
